Application March 10, 1943, Serial No. 478,660

1 Claim. (Cl. 102—38)

(Granted under the act of March 3, 1883, as amended April 30, 1928; 370 O. G. 757)

1

The invention described herein may be manufactured and used by or for the Government for governmental purposes without the payment to us of any royalty thereon.

This invention relates to projectiles for firearms, and more particularly, to the type of projectile having a jacket usually of copper or other non-ferrous material the outside diameter of a major portion of which measures to the calibre of the firearm but which is provided with a smaller portion or portions of a diameter larger than the barrel calibre at the gun muzzle. This enlarged jacket portion or portions is reduced during its passage through the tapered bore of the gun, by a crushing action upon the comparatively soft jacket material, down to the actual muzzle calibre; for this purpose, the gun barrel has a section following the breech and cartridge section, of sufficient diameter to receive the enlarged jacket portion or portions. The gun barrel is reduced or tapered, in one or more stages, from the said enlarged section to the gun calibre at the muzzle.

The range and momentum of the projectile depends chiefly upon the pressure developed upon the explosion of the propellant and the area of the projectile presented to that pressure. In the ordinary type of projectile of outside diameter equal to that of the gun calibre, the effective area is the cross-sectional area corresponding to the outside diameter of the jacket. This area cannot be enlarged, for ballistic reasons: the air resistance and other effects and forces present in flight increases with increase in projectile diameter (calibre). In the type of projectile referred to, additional area to receive the pressure engendered by the explosion is provided by the enlarged portions of the jacket. As stated above, this enlarged jacket portion is reduced during passage through the bore of the barrel down to the gun calibre, so that no part of the enlarged jacket will be present during flight.

One of the objects of this invention is to provide an improved projectile of the type referred to. How the projectile is improved will be apparent from the accompanying drawings; wherein:

Figure 1 is a longitudinal section through one form of improved projectile in position in its cartridge shell;

Figure 2 is a longitudinal section of the projectile of Figure 1 in flight;

Figure 3 is a longitudinal section through another form of improved projectile in position in its cartridge shell;

2

Figure 4 is a longitudinal section of the projectile of Figure 3 in flight;

Figure 5 is a cross-sectional view on line 5—5 of Figure 3; and

Figure 6 is a diagram of the forces acting upon a projectile in flight.

The invention is illustrated in Figures 1—2 and Figures 3—4—5, in connection with armour-piercing projectiles, which differ from ball projectiles in the nature of the core, the core in both cases being contained in a suitable jacket such as copper, brass or gilding metal: The core in the common ball projectile is lead, whereas heat treated steel is used in armour-piercing projectiles. The core 20 in Figures 1—2 and the core 20 in Figures 3—4—5 represent heat-treated steel suited for armour piercing purposes. The projectile may comprise only core and jacket as in the species of Figures 3—4—5 or it may have, in addition, a "point filler" 9 of lead as in Figures 1—2. It should be understood, however, that the invention may be applied to ball (lead core) projectiles.

The jacket of Figures 1—2 is constructed of two sections, a main section 10 and a considerably smaller section 19 at the nose of the projectile which might conveniently be termed the "windshield cap." The right end of main jacket 10 is bellied out to form an annular rib 11 which is readily fabricated from the regularly-shaped jacket by first cutting the same to form the said two parts (main jacket 10 and windshield cap 19) and then flanged to form the annular rib 11. As clearly seen in Figure 1, the free edge 11e of the flanged rib 11 makes contact with the surface of core 20, and is removed from the edge of the windshield cap 19 by a clear space, designated 1.

The left or rear end portion of the jacket is formed as a skirt 13 of enlarged diameter, equal to the diameter of the annular rib 11. The jacket portion between skirt 13 and rib 11—i. e., the waist portion 12—is soldered or sweated 22 to core 20; to ensure a firm securement the core may be knurled or otherwise roughened.

The area of the projectile effective to receive the explosive pressure is thus increased from diameter *f* which it would have in ordinary projectiles to enlarged diameter *e*. During its passage through the barrel of the gun, the annular rib 11 and skirt 13 are reduced down, in the manner explained above, to the uniform diameter *f* which is equal to the calibre of the gun, and the diameter of the projectile in flight (see Figure 2). During the reducing operation, the

front annular flange or rib 11 is flattened down, with its edge 11e touching, or close to the rear edge of windshield cap 19. In the reducing or flattening out operation, the jacket 10 is prevented from moving rearwardly by the soldered or sweated fastening 22 to the core 20. The seated fastening of the jacket on the core thus serves two functions, viz., (a) the one just mentioned in the flattening operation, and (b) to prevent twisting of the jacket on the core during the rifling of the jacket as the projectile passes through the rifling portion of the barrel. The skirt portion 13 is reduced or deformed down to uniform diameter f as shown in Figure 2.

For the purpose of presenting an enlarged area to the propellant pressure either the skirt 13 or annular rib 11 would suffice. Both are used for a further reason, namely, to provide two points of support for the projectile during its passage through the enlarged part of the gun barrel, and thus to eliminate lateral or sidewise movement of the projectile, which would be possible were a shorter base of contact provided. The cartridge shell, part of which (8) is shown in the figures, is clipped at 7 over the beveled portion 13b of the skirt (see Figure 1).

It will be observed from Figure 1 that the skirt 13 extends a short distance to the rear of core 20. After the reducing down of the jacket in its passage through the gun, i. e., when the projectile is in flight, this skirt extension will be somewhat increased; the skirt extension is designated 13x in Figure 2. The purpose of skirt extension 13x will be explained with the aid of Figure 6 which shows the forces acting upon a projectile in flight. These forces are chiefly, in addition of course, to the momentum of the projectile, the force of gravity W acting upon the center of gravity g and the resultant forces due to relative wind resistance R which acts upon a point p known as the center of pressure, which is always displaced a considerable distance away from the center of gravity. As a result thereof, a torque or couple is created, being the resultant force R at the distance arm between g and p depending upon the position or displacement of the resultant force. This couple tends to cause the projectile to turn in its flight about point g (through angle a). It is a desideratum, therefore, to bring the center of pressure p as close as possible to the center of gravity g in order to keep the aforesaid couple as small as possible.

This is achieved in the improved projectile of Figures 1-2 by extending the jacket alone, by means of its skirt extension 13x without increasing the length of core 20. The increased surface presented to the wind at the rear (left in Figures 1-2) of the projectile causes the center of pressure of the projectile to be brought further to the rear of the projectile and hence closer to the projectile's center of gravity.

The projectile of Figures 3-5 differs from that of Figures 1-2 in that, instead of two points of support afforded by skirt 13 and annular rib 11 (thus constituting an effective base from point 13 to point 11), a single base is provided. As shown in Figure 3, the rear of jacket 40 is enlarged to form a bulbous portion 42 connected to the front jacket portion by a bevel 41. The bulbous portion 42 extends over a considerable part of the core to afford a sufficient base functioning in the projectile's passage through the barrel, as explained above. The rear end of the

bulbous jacket 42 is provided with a flange 44 which projects normally and inwardly from cylindrical portion 42, through a curve or fillet 43. The rear end of core 20 has a cupped depression 35; and the edges of flange 44 is pressed back at 45 to be received at the periphery of core cup 25. The distance between the flange edges is designated "d" in Figure 3, the opening being circular (see Figure 5). The rear edge of the core is also rounded as indicated at 23.

The jacket may be secured to the core by sweating as in the core of Figures 1-2. The core 20 has in addition, one or more flats 21 which serve to prevent twisting of the core in its jacket. The cartridge shell 8 is clipped over the bevel 41 of bulbous jacket 42, at 7, Figure 3.

The rear end of bulbous jacket 42 has one or more port holes 46 to expel the air in the annular space between jacket and core, when the bulbous part is flattened down. As shown in Figure 5, three such holes 46 are provided, symmetrically arranged as equally spaced from each other. When reduced by passage through the gun, the bulbous portion will be entirely eliminated (see Figure 4), except for the rear inward flange 44, the edges 45 of which will touch, or almost touch, as shown in Figure 4. It will be noted that the fillet 46 of the jacket flange, the rounded edge 23 of the core and the cupped depression 25 of the core, all aid in directing the bulbous jacket in a manner to more or less completely encase the rear end of the core.

We claim:

In a cartridge comprising a cartridge shell and a projectile of the type having a core and a deformable jacket, a portion of which is of enlarged diameter receivable in the breech end of a gun barrel, the said barrel having an initial section adapted to reduce the said enlarged jacket to the calibre diameter at the muzzle end of the barrel, the combination of a dual-sectioned jacket having a main section and a shorter forward section at the projectile nose, the said main jacket being bellied out near its forward end to form an annular rib of enlarged diameter, and provided with a skirt of substantially the said enlarged diameter of the annular rib, a portion of which extends beyond the rear end of the said core, the said annular rib and the said skirt being separated by a reduced waist portion in contact with the core, the said cartridge shell being clipped to the annular flange provided at the junction of the said waist and skirt portions of the jacket.
